ROOF STRUCTURE

William A. Halicki, Detroit, Mich., and Donald B. Gordon, Corvallis, Oreg., assignors to National Steel Corporation, a corporation of Delaware

Application May 3, 1943, Serial No. 485,417

5 Claims. (Cl. 108—13)

The present invention relates to sheet metal roofing and roof structure and more specifically to a new and improved form and arrangement of parts by the use of which an improved roof structure may be produced.

A large number of forms of metal roofing have heretofore been devised, but those which have proved commercially satisfactory have heretofore been of complicated construction. It is, therefore, a primary object of the present invention to provide a type of roof and roofing structure which is greatly simplified both as to manufacture and assembly.

A further object of the present invention is the provision of a readily demountable roof structure which is inexpensive to manufacture, and easily assembled in the field by ordinary workmen without the need for special tools.

A further important object of the invention is the provision of a roof formed of panels detachably connected together to present a strong and rigid construction.

A further important object of the invention is the provision of a prefabricated panel for incorporation in a roof construction.

A still further object of the invention is to provide an improved form of ridge member adapted to interlock with the upper portions of the roof panels.

A still further object of the present invention is to provide an improved form of eaves structure adapted to have interfitting engagement with lower portions of the roof panels.

Other objects of the invention will become apparent to those skilled in the art from the following detailed description taken in connection with the accompanying drawings which disclose a preferred embodiment of the invention.

Figure 1 is a vertical sectional view of a lower portion of the roof of the present invention;

Figure 2 is a plan view of the construction shown in Figure 1;

Figure 3 is a vertical sectional view of an upper portion of the roof of the present invention;

Figure 4 is a sectional view of the construction of the roof at the gable;

Figure 5 is a sectional view taken on the line 5—5 of Figure 1;

Figure 6 is a sectional view taken on the line 6—6 of Figure 1;

Figure 7 is a front view of a portion of the structural element forming a part of the roof panel; and

Figure 8 is a sectional view thereof.

Referring to the drawings, the roof is made up of a plurality of panels 10 of novel construction. As seen in Figure 6, each panel is made up with special structural elements herein sometimes termed modified C-shapes. Each C-shape is formed of a web 12, flanges 13 and flange exten-

sions 14 inclined at an acute angle to the flanges 13. An external sheathing member 15, which may be of any desirable material but preferably metal, is provided with flanges 16 arranged at an acute angle to the plane of the sheathing member. A structural member 11 is tacked or integrated to sheathing member 15 in any suitable manner, preferably, if sheathing member 15 is formed of metal, by a line of spot welding 17 between flange 10 of the C-shape and the sheathing. As seen in Figure 1, sheathing 15 is provided at its lower edge with a downwardly inclined flange 18 having a reversely bent extension 19 terminating in a short section 20 spaced from the lower face of the sheathing member a distance equal to the thickness of the metal for a purpose to be later described. The upper edge of the sheathing is provided with a flange 21 forming an angle with the surface of the sheathing. In final assembled position this is an acute angle (Figure 3).

Figure 6 shows the manner in which two adjacent panels are joined together to form a weather-tight joint. With the ends of the two panels contiguous and the C-shapes arranged with the web portions in contact, a spline or key member 22 having flanges disposed at angles corresponding to the angles of sheathing flanges 16 is slid into locking position as shown.

In Figure 4, a modified form of panel to be used at the gable ends of the roof is shown. In this form, the sheathing 23 has one edge provided with an upturned flange 24 similar to panel flange 16 in order to receive a spline 22. The other edge of sheathing 23 has a downwardly directed flange 25 secured to a gable member 26 by means of self-threading screws 27. As seen in this figure, additional securing means in the form of spot welding 17 may be used.

Referring to Figure 3, the ridge roll or cap 28, which extends the length of the roof, is shown as being formed with a circular roll 29 and extending flange portions 30. Flange portions 30 are reversely bent to form rearwardly extending portions 31 lying against flange portions 30. Portions 31 are bent downwardly to form inclined walls 32 and then forwardly to provide portions 33. The distance between portions 33 and 31 is substantially equal to the thickness of spline member 22. The angularity of inclined wall 32 is complementary to the angularity of panel flange 21 in order that wall 32 may lie against and contact flange 21.

Referring to Figure 1, the space between the edge of the roof and the walls of the shelter may be covered by a specially constructed eaves member 34 which may run the length of the roof. The eaves member comprises a web portion having a depending flange 35 secured to wall 36 by means of self-threading screws 37 and an upper flange

41 frictionally received between flange 20 and the lower surface of sheathing member 15.

As shown in Figure 1, the roof supporting means/comprises a plurality of channel shaped horizontal beams 39. Each beam consists of a web portion 40 and upper and lower flanges 41 and 42. Self-threading screws 43 pass through lower flange 42 and fasten the beams to channel member 44 forming a part of the wall structure of the shelter. The outer ends of the beams are suitably cut away to accommodate the sloping roof and inclined eaves member.

The roof of the present invention is carried by a novel wall structure forming a separate invention disclosed in copending application Serial No. 485,416, filed May 3, 1943, by the present inventors.

In assembling the roof of the present invention, the beams 39 are laid across the top of the wall structure and secured thereto by screws 43. The roof panels are then assembled as seen in Figures 1 and 3 by bolting the web portions 12 of complementary panels to each other by bolts 45 to form the sloping roof. The opposite ends of these web portions are bolted by bolts 46 to the ends of the corresponding beam 39. Splines or key members 22 are then slid into position with the upper ends tightly received in the space between flange portions 31 and 33 to form a weathertight joint between adjacent panels. The ridge cap 28 may then be slipped into position with flange 21 being bent into snugly engaging relation with flange 32 as seen in Figure 3. The eaves members are then applied by inserting flange 41 into the space between flange 20 and the panel sheathing and securing flange 35 to the wall structure by means of the self-threading screws 37.

The roof may be taken down by merely reversing the above steps.

We claim:

1. A roof construction comprising a series of beams having spaced ends, a series of juxtaposed roof panels, each panel including a sheathing member having an upper edge, an eaves edge and a pair of panel mating edges, each panel presenting upwardly turned reversely bent flanges extending for the full length of each panel mating edge, structural elements on the underside of each panel, each structural element presenting a flange and connected web, the flange of a structural element being integrated to the sheathing member along each panel mating edge, removable fastening means acting between webs of adjacent structural members and the beam ends to hold the roof panels together to form a roof, and imperforate splines having downwardly and inwardly directed flanges embracing the upturned flanges of adjacent panel mating edges throughout the length of such edges to seal the joints between roof panels.

2. A roof construction comprising a series of beams having spaced ends, a series of juxtaposed roof panels, each panel including a sheathing member having an upper edge, an eaves edge and a pair of panel mating edges, each panel presenting upwardly turned reversely bent flanges extending for the full length of each panel mating edge, structural elements on the underside of each panel, each structural element presenting a flange and connected web, the flange of a structural element being integrated to the sheathing member along each panel mating edge, removable

able fastening means acting between webs of adjacent structural members and the beam ends to hold the roof panels together to form a roof, imperforate splines having downwardly and inwardly directed flanges embracing the upturned flanges of adjacent panel mating edges throughout the length of such edges to seal the joints between roof panels, and a downwardly directed extension on the eaves edge of each panel, the extension being bent first toward the underside of the sheathing member and then bent in the opposite direction to provide a connecting section and a section adjacent but spaced from the underside of the sheathing member, and an eaves member having a flange snugly received in the space between the last named section and the sheathing member.

3. A roof construction comprising a series of beams having spaced ends, a series of juxtaposed roof panels, each panel including a sheathing member having an upper edge, an eaves edge and a pair of panel mating edges, each panel presenting upwardly turned reversely bent flanges extending for the full length of each panel mating edge, structural elements on the underside of each panel, each structural element presenting a flange and connected web, the flange of a structural element being integrated to the sheathing member along each panel mating edge, removable fastening means acting between webs of adjacent structural members and the beam ends to hold the roof panels together to form a roof, imperforate splines having downwardly and inwardly directed flanges embracing the upturned flanges of adjacent panel mating edges throughout the length of such edges to seal the joints between roof panels, and a ridge cap, a flange on the ridge cap, the ridge cap flange having a reversely bent portion, resting on the splines, a downwardly directed portion, and a portion resting on each sheathing member, the upper edge of the sheathing member presenting an upturned flange snugly engaging the downwardly directed portion of the ridge cap flange.

4. A prefabricated roof panel comprising a sheathing member having an eaves edge and a pair of panel mating edges, upwardly turned reversely bent flanges extending for the full length of each panel mating edge and structural elements on the underside of the panel, each structural element presenting a flange and connected web, the flange of the structural element being attached to the sheathing member along each panel mating edge.

5. A prefabricated roof panel comprising a sheathing member having an eaves edge and a pair of panel mating edges, upwardly turned reversely bent flanges extending for the full length of each panel mating edge and structural elements on the underside of the panel, each structural element presenting a flange and connected web, the flange of the structural element being integrated to the sheathing member along each panel mating edge, and a downwardly directed extension on the eaves edge of the panel, the extension being bent first toward the underside of the sheathing member and then bent in the opposite direction to provide a connecting section and a section adjacent but spaced from the underside of the sheathing member.

WILLIAM A. HALICKI.
